Jordan L. Mott, a New York City

Letters Patent

The Schedule referred to in these Letters Patent and making part of the same containing a description in the words of the said Jordan L. Mott of his improvement in the manufacture of Knobs or handles to be applied to Stoves and Grates.

To all whom it may concern. To be it known that of Jordan L. Mott, of the City of New York in the State of New York has invented a device or new and improved manufacture of Knobs or handles to be applied to Stoves and grates of various descriptions and to other purposes, and to have by virtue that the following is a full and exact description thereof.

My new manufacture consists in the employment of a material for making knobs or handles used for the above named purpose, which material is the metal commonly called Spelter. And such knobs or handles either in round, square, pointed or any round and or square, hollow pieces and units, are joined together by means of pins or screws passing through them in the manner ~~commonly~~ ^{commonly} in uniting the parts of traps and other parts employed for trapping and other purposes. What I claim as my invention is the manufacture of knobs or handles used about grates and Stoves and for other purposes, which have heretofore been made of brass, zinc, or spelter as above described by which the cost of them is much diminished whilst they are equally well adapted to the intended purpose. This done and having been fully done. June 1835
